A. E. FRANCIS.
ELECTRIC SWITCH.
APPLICATION FILED OCT. 2, 1917.

1,303,876.

Patented May 20, 1919.

UNITED STATES PATENT OFFICE.

ARTHUR E. FRANCIS, OF CLEVELAND, OHIO.

ELECTRIC SWITCH.

1,303,876.

Specification of Letters Patent. Patented May 20, 1919.

Application filed October 2, 1917. Serial No. 194,393.

To all whom it may concern:

Be it known that I, ARTHUR E. FRANCIS, a citizen of the United States, residing at Cleveland, in the county of Cuyahoga and State of Ohio, have invented certain new and useful Improvements in Electric Switches, of which the following is a specification.

This invention relates to electric switches, and particularly to a switch adapted to be attached to the steering post of an automobile. The location of a switch on a steering post, just above the steering wheel, is very convenient for operation by either hand of the driver, and the object of the present invention is to provide an improved switch which may be quickly and easily mounted on the steering post, in the position indicated.

20 The device is especially designed for the Ford automobile, but may be used on other machines with little or no modification.

The accompanying drawing is a vertical section of the switch, showing the same applied to the steering post of an automobile.

Referring specifically to the drawings, 1 indicates the steering post and 2 the steering wheel secured thereto by a nut 3 which screws on the threaded end of the post.

30 The switch casing is indicated at 4, and is preferably made of metal. The upper end of this casing is circular, and the lower end 5 is hexagonal, to fit closely over the nut 3 to which it is fastened by screws 6 fitting 35 tapped holes in the sides of the nut. Obviously the shape of the casing may be varied to fit the nuts on knobs of various types of steering posts.

Within the casing is a block 7 of insulating material which has recesses on the under side and rests on the top of the nut 3. A spring contact piece 9 is mounted on top of the block 7 by a rivet 10 which is connected to a binding screw 11 by a small plate 45 12, and the screw 11 also connects the wire

13 leading to the horn or other signal not shown. Another contact piece 15 is held on top of the block by a rivet 16 and connected by a small plate to the binding screw 18 which may be grounded or connected to a ground wire if two wires are used. The contact piece 15 has a downwardly projecting arm 15^a which connects to the fastening screw 6, which forms a ground when only one wire is used. A recess 14 on the under side of the block permits the passage of the wires.

50 A button 20 fits upon or above the casing and has a depending flange 21 which surrounds the edge of the casing to exclude water. This button is attached to a circular plate 22, which fits within the casing and is held therein by a flange 23 at the upper edge, by a rivet 24. This rivet 24 rests on the spring 9 which normally acts to hold 55 the button in raised position with the contacts open.

When the button is pressed down the contacts 9 and 15 are closed, to close the circuit and operate the horn or other device.

60 The switch can be easily applied to or removed from the steering post, and is supported in a very convenient position for the operation.

I claim:

70 The combination with a steering post having a nut at the top thereof, of a switch comprising a shell shaped to fit around and inclose said nut, a block resting on the nut and confined thereto by the shell, contacts supported by the block, and a push button mounted on the top of the shell and arranged to close the contacts.

75 In testimony whereof, I do affix my signature in presence of two witnesses.

ARTHUR E. FRANCIS.

Witnesses:

ETHEL A. JOHNSTONE,
EARLE E. WHITE.
